**PROCESS OF REMOVING COLOR FROM COTTON
SEED OIL AND THE LIKE**

Porter A. Williams, Houston, Tex.

Application January 30, 1953, Serial No. 334,172

6 Claims. (Cl. 260—425)

This invention relates to a process of removing color from vegetable oils such as cotton seed oil, peanut oil, linseed oil, soya bean oil, sesame oil, and the like.

It is an object of this invention to provide a process of removing color from cotton seed oil, and the like, by re-refining methods which comprise the substantially instantaneous dispersion of a caustic solution into the oil whereby the color bodies of the oil may be so amply and intimately contacted by a minimum quantity of the caustic refining agent with a resultant maximum removal of color bodies at a minimum refining loss.

It is another object of this invention to provide a process which maintains the oil and caustic in a closed system whereby their substantially instantaneous mixture is accomplished without the incorporation of excessive air.

It is still a further object of this invention to provide a process which utilizes caustic soda solutions in high concentrations above 40° Baumé and somewhere near the point of saturation for the governing temperature and by minimizing fat saponification and improving the effectiveness of color removal, such solutions being maintained at temperature above the critical minimum temperatures required to maintain the caustic in solution.

It is yet another object of this invention to provide a process of this class which permits the oil to be re-refined at a wide range of temperatures.

It is also another object of this invention to provide a process of this class which employs as a mixing device a machine having mechanical rotor means rotatable at excessive speeds to agitate the oil and caustic to be mixed within the limited space or passageway.

It is yet a further object of this invention to provide a process of this class in which the mixture of oil and solution in passing by high speed rotatable means passes through a passageway which is subject to adjustment of opening down to a point of grinding contact.

It is yet another object of this invention to provide a process of this class which may employ pressures to force the mixture through a passageway of the machine which pressures vary in accordance with the structural limitations of the machine, the passageway opening and the throughput.

It is still a further object of this invention to provide a process of this class in which the throughput of the machine is a function of the head pressure and the width of the passageway opening.

It is also a further object of this invention to provide a process of this class in which the mixture from the machine may be subsequently treated so as to utilize either separation by gravitation or by a continuous process involving the use of centrifugal separation.

It is yet another object of this invention to provide a process of this class in which the mixture of oil and solution passes through passageways providing abrasive surfaces.

It is yet a further object of this invention to provide a process of this class in which the mixture of oil and solution passes through passageways, the component wall

2

forming parts of which comprise highly relatively rotatable means.

It is yet another object of this invention to provide a process of this class in which the oil is mixed with caustic soda solutions of such high concentrations as to produce a lighter colored oil than heretofore obtainable.

It is an object of this process through the substitution of a thorough dispersion for conventional mixing to provide a continuous process when used in conjunction with centrifuges wherein a simplification of machinery either by an increased capacity is achieved per unit machine or a simplification of machinery is achieved through substitution of one unit for a multiplicity of mixing units.

It is an object of this invention to provide a batch process for decolorizing oil wherein through the use of a most effective dispersion treatment it eliminates the effect of the contact time element thereby providing a process of high capacity associated with a minimum investment and unit machinery requirement.

It is yet a further object of this invention to provide a process of this class in which the mixing step is accomplished in a matter of seconds, a second or fractions of a second as compared with the conventional methods heretofore employed which require several minutes in the mixing step.

It is yet a further object of this invention to provide a process of this class which may optionally employ a blender prior to the high speed mixing step.

It is also another object of this invention to provide a process of this class in which the mixture of oil and caustic is so produced that the subsequent time elapsing between the mixing step and the completion of the process has no further effect upon the loss sustained.

In processing some cotton seed oil and the like by conventional refining methods, regardless of the efficiency of the method, some oils will have a dark, refined oil color which cannot be readily bleached by conventional bleaching methods. Such oils have a limited use unless they are subsequently subjected to another refining process to improve their bleachability, and this subsequent process is termed the re-refining or lye-washing process.

In general, the lye-washing process comprises mixing the oil with a predetermined quantity of relatively weak lye. Then, after the expiration of a certain agitating time, with or without the subsequent addition of water, the agitation is discontinued. Then, the aqueous phase, containing neutralized acids and some fat and coloring matter, is allowed to settle and is subsequently drawn off. This conventional lye-washing has been carried out by two types of processes; one being a batch process involving separation by gravitational settling; the other being a continuous process involving the use of centrifugal separation.

The batch process of re-refining consists essentially of adding a small quantity of caustic soda in concentration up to saturation, stirring the mixture from one-half to three hours. After expiration of desired mixing time and while the agitation is still continuing, water is added in such quantity as to produce a soap which readily agglomerates when the agitation is slowed and settles when it is discontinued. Separation is gravitational and takes place in a relatively short time.

The second method of re-refining consists of mixing oil and relatively weak lye in concentration usually lying between 14° and 24° Baumé, while the oil and lye are traveling through a continuous mixer the period of agitation is relatively short, usually in the neighborhood of five minutes. The oil and lye mixture is heated, either before or after mixing, usually after mixing, and is then subjected to centrifugal separation for purposes of removing the semi-solid soap stock from the refined oil.

In exploring the possibility of improvement of the batch

process, Kavanagh, in his publication in "The Journal of the American Oil Chemists Society," September 1951, made the following observations: "The efficiency of color removal is directly proportional to the strength of caustic soda used, the length of time of high speed stirring, the amount of caustic soda used, and the speed of agitation, but inversely proportional to the temperature of the oil-caustic soda mixture." No comparative loss figures were given; however, statements were made to the effect that refining loss increased rapidly when the amount of alkali added was increased, especially with high concentration of sodium hydroxide solutions; refining loss increased only slightly at low temperature but increased rapidly at high temperature as the time of agitation was prolonged. "Relatively larger percentage of 20° Baumé or weaker caustic soda solution can be used at temperatures below 85° F. without encountering undue enlarged refining losses and with higher concentration of caustic soda solution it is essential to use the minimum percentage by weight of alkali in order to avoid undue high refining losses."

Kroonen, in a publication in "The Journal of the American Oil Chemists Society" of February 1952, and after the process of this invention was developed, on pursuing the type of re-refining proposed by Kavanagh, again showed that oils re-refined by a so-called "high-sheer" method showed less residual color than conventionally re-refined oils; their color removal was most rapid during the first five minutes and practically complete in ten minutes; the optimum concentration of lye for color removal was between .1 and .2 percent sodium hydroxide; that optimum concentrations of sodium hydroxide was between 20° and 30° Baumé; that color removal improved as the temperature dropped and that losses encountered by this method of re-refining were almost identical to those losses encountered by conventional methods.

It can be seen that this invention departs in substance and theory from both Kavanagh and Kroonen as to its method steps and as to its obtained results. In such invention the refined oil is fed by gravity or pumped under superatmospheric pressure through a flow measuring device into a conduit. Caustic from above 40° to 60° Baumé, preferably in the form of a fully saturated solution in the neighborhood of 50° Baumé, is likewise by means of gravity or under superatmospheric pressure fed through a metering device into the same conduit. This mixture then flows into a mechanical mixing device; such as (but not limited to), a conventional cone blender, rotating at about 900 R. P. M. This first mixing device is used to put the two immiscible solutions in condition so as to insure the effectiveness of the following critical treatment, and is an optional step.

The mixture is passed from the first preliminary blender into the dispersing device, one form of which consists of a set of stones; one fixed and one rotating. These stones are capable of adjustment with reference to the spacing between them. The mixture, in passing through the regulated spacing between the stationary and moving stones is subjected to an attrition which brings about a degree of dispersion; unobtainable by other means.

After being subjected to this dispersion treatment, the mixture may be treated either by a continuous or a batch process.

If treated continuously, the mixture is heated either before or after the admixture of sufficient water to bring the soap into a condition susceptible to centrifugal separation of oil from soap phase, a condition which is ordinarily carried out between 100° and 170° F.

If carried out on batch process, the mixture is allowed to accumulate to the desired size batch and then is treated and admixed with water either before, after or during the heating. Sufficient water is added so that when the soap is agitated sufficient to keep it suspended within the oil phase it agglomerates to particles of such size and density as to make it bring about a satisfactory separation through gravitation.

As shown in Fig. 1, the oil or liquid to be refined, is stored in tank 1 from which the line 2, having the control valve 3 therein, extends for connection to the suction side of the pump 4. This pump 4 discharges into the line 5, having the control 6 therein, and is supplied into the metering device 7 from which is flows, via the line 8, having the control valve 9 and check valve 10 therein, to a blender 11.

The caustic tank 12 containing a saturated solution of NaOH, normally about 50%, at room temperature, has the line 14 therefrom, having the control valve 15 therein, which is connected to the suction side of the pump 16. The pump 16 discharges through the line 17 having the strainer 18 and control valve 19 therein, to the metering device 20. From the metering device 20, the caustic passes via the line 21 having the control valve 22 and check valve 23 therein, into the line 8 to join the oil therein, and to flow with the oil to the blender 11.

The blender 11 forms a homogeneous admixture of the two immiscible liquids and via the line 24, having the strainer 25 therein, it supplies the admixture to the junction of the line 26 and the line 27. If it is desired to recirculate the admixture until such time as the proper oil and caustic balance is obtained, the valve 28 is closed and the valve 29 is opened so that the admixture may flow back into the oil storage tank 1. The valve 30 is normally opened to admit the pressure of the liquid in the line to act on the gauge 31.

If it is desired to discharge the fluid directly to the fluid dispersator 32, the valve 29 is closed and the valve 28 is opened. In this machine the admixture is rotated at extremely high speeds, as 5400 R. P. M., and passes by a paddle structure which acts as an agitator. It then passes through an angularly extending passageway between a stationary stone and a rotatable stone revolving at say 5400 R. P. M., such passageway being normally not greater than $\frac{1}{2}$ " in width.

The speed of the revolving stone may vary between 900 R. P. M. and 15,000 R. P. M., depending upon desired throughput. Moreover, the oil-caustic mix may be added under a pressure varying from at least atmospheric to approximately 100#/sq. in., again depending upon throughput and stone spacing. Conversely, the rate of throughput may vary between 5000#/hr. and 42,000#/hr., or higher, depending upon pressure and stone spacing. The stone spacing may vary between almost actual contact and $\frac{1}{4}$ ", or even greater. The construction of the dispersator, in detail, will be described hereinbelow.

The finely divided caustic is dispersed into the oil, where it reacts with the color bodies to facilitate their separation from the main body of the oil.

The discharge 33 is so constructed, that the air is easily and quickly removed from the dispersator. This is possible since the fluid communication area between the dispersator and the inverted U-shaped pipe 34 is great, so that air from the dispersator will rise upwardly therein as the chamber fills with oil.

From the U-shaped pipe 34, having the valve 35 therein, the mixture may discharge through the line 36 to conventional centrifugal machines, or optionally it may discharge through line 37, having the valve 38 therein, to the kettle 39 where the process of re-refining is completed.

The line 36 has the valve 48 therein between its junction with the line 37 and the heat exchanger 50, which serves to cool the discharge from the dispersator 32. From the heat exchanger 50 the line 36 leads to the centrifuge separator 51 which serves to separate the oil from the soap and saponified residues, the soap being discharged at 52 and the oil at 53.

To supply water to the line 36, the line 54 is provided having the check valve 55 and valve 56 therein.

In case it may be desirable to wash out the caustic system, the valves 44 and 45 in the line 46 are opened, the line 46 also having the check valve 47 therein adjacent the valve 44. Also the valve 42 in the line 41 is

closed, such line also having the check valve 43 therein. Also the bleeder valve 40 in the line 49 is closed, as is the valve 15 in the line 14. Then compressed air is injected into the line 46 to blow out the system. After this the valve 44 is closed and the valve 42 is opened to admit water to wash out the system.

The details of the dispersator are shown in Fig. 2, disclosing one form of machine for carrying out the step of throwing a small quantity of concentrated caustic into intimate fixing contact with the color bodies. The principles on which machines of this type work consist of bringing the oil and caustic mixture into contact with a rapidly revolving means operable in a limited space to complete the complete intermingling of the caustic and oil, and thereafter passing the intermingled oil and caustic through an orifice of very restricted character between two relatively rotatable elements, preferably abrasive stones.

The relative rotation may be obtained by rapidly revolving one element, or stone, with relation to a fixed element or stone, when there is a very limited passage or orifice between such elements. Optionally both elements may be rotatable in the same direction but with a wide degree of relative rotation being obtainable between the high speed and low speed elements. Also, the desired great relative rotation may be obtained by revolving one element, or stone, in one direction, and the other element, or stone, in the other direction.

In detail the dispersator 32, shown in Fig. 2, comprises the housing 60, which, as shown, may be mounted vertically, although this invention considers machines which may be mounted with axis to extend horizontally, as well. The intermingled oil and caustic enters the inlet 61 from the line 27, and is brought into contact with the rapidly revolving impellers or paddles 62 in the mixing chamber 63. If, at this point the oil and caustic have not yet been thoroughly intermixed and intermingled, such is accomplished to completion in this chamber.

The housing 60 is mounted on the motor 64 which has its shaft 65 coupled, by the coupling 66, to the shaft 70. Surrounding the coupling is an externally toothed ring gear 67, which is integrally connected to the sleeve 68, which is threaded at 69 into the housing 60. The sleeve 68 has the internal shoulder 71, which underextends the external shoulder 72 of the shaft 70 and the lower ball bearing assembly 73.

The shaft 70 has the splines 74 thereon which fit into grooves 75 in the inner or wear sleeve 76, which wear sleeve extends between the lower ball bearing assembly 73 and the upper ball bearing assembly 77. The backing member 78 rests downwardly on the inner race of the lower ball bearing assembly 73 and the spacer member 79, and the sleeve 68 has the upper extension 80 which confines the spacer member 79 and outer race of the upper ball bearing assembly 77 in position.

The pinion shaft 81 is supported in the housing 60 outwardly of the gear 67, and the pinion 82 thereon meshes with the gear 67. Thus, by turning the pinion shaft handle 83 in the proper direction the pinion 82 causes the gear 67 to rotate, and since the sleeve 68 is integrally connected to the gear 67, and is threaded at 69 into the housing 60, the sleeve 68 moves upwardly in the housing, and with it the sleeve shoulder 71 lifts the shaft 70 and the lower ball bearing assembly 73, and the wear sleeve 76, and the elements supported thereabove.

At the same time the pinion 82 maintains engagement with the gear 67 by virtue of the width of the face of such gear, and the shaft 70 maintains connection with the motor drive by virtue of its lower end being splined at 83 to fit in grooves in the coupling 66.

The backing member 78 supports, and has connected thereto, a disc element 84, which, in certain original usages of this type of machine, served as a grinding element, and such element was naturally of an abrasive substance, as Carborundum or stone. In the present usage such element 84 is shown to be of an abrasive substance, but the mate-

rial thereof is not necessarily a limitation, and other substances may be employed and formed to the configuration to be hereinbelow described.

Such configuration comprises a flat base to rest upon the backing element 78, a tapered portion, and a flat top. The insert 87 is pressed into the disc element 84, and has the flange 88 at the lower end thereof to bear upon the shoulder 89 of the shaft 70. The shaft, in turn, is firmly connected to the insert 87, either by being pressed 10 thereinto, or by other connection means. As shown, the impellers or paddles 62 are connected to the disc 90, through which the shaft section 91 passes, while such disc shoulders on the insert 87. Finally, the nut 92 is threaded onto the shaft section 91 to complete the rotor assembly 99.

The housing cap 93 has the recess 94 therein into which is fitted the annular member 95 having the backing plate 96 thereon. Such member can be of the same material as the disc element 84, and this is shown in Fig. 20. The annular member 95 has a countersunk inner surface to oppose the tapered surface of the disc element, and a flat lower surface to oppose the flange face of the disc element base.

It can thus be seen that by turning the handle the shaft 25 70 and the elements assembled thereon and therearound may be moved axially to vary the spacing between the disc element and the annular member. Thus the orifice can be varied from the vicinity of grinding contact to some spacing, as indicated in exaggerated extent in Fig. 30 2, which may vary from almost grinding contact to $\frac{1}{4}$ ", or greater, depending upon the desired throughput.

The fluid to be processed in the dispersator, as the mixture of oil and caustic, enters from the line 27, via the inlet 61 into the dispersator mixing chamber 100, and 35 passes by the impellers 62 and through the annular orifice 101 into the discharge chamber 102 from whence it passes, via the outlet 33 into the tube 34. A coolant, as water, enters through the line 103, into the coolant chamber 106, from whence it communicates, through 40 passages, not shown, with the jacket 105. From the coolant chamber 106 the coolant departs, via the discharge line 104, the oil-caustic mixture being maintained at a temperature of 60° to 150° F., a range of 70° to 110° F. being preferred.

In case it might be desired to provide that the speed differential between the disc element 84 and the annular member 95 should be provided by also rotating the annular member, any suitable conventional drive, not shown, could be provided to also rotate this member, and at 50 different speeds from the disc element. Such differential could be provided by rotating the annular member at greater speeds, or at lesser speeds than the disc element, or in opposite direction from the direction of rotation of the disc element.

In this regard it is only necessary that excessive velocities be obtained as in this way a very small volume of a more concentrated solution of caustic may be used, and through the excessive agitation or rate of circulation imparted thereto due to its passage with the oil and the color bodies therein, through the restricted annular orifice, such caustic is assured of being thrown into intimate contact with substantially all of the color bodies, even though by volume such color bodies are even less than the small amount of higher concentrate of caustic employed.

In summary, the excess movement imparted to the mixture of caustic and oil containing color bodies therein, in the minimum time required for passage through the orifice, insures that, regardless of what small percentage the caustic may bear to the oil by volume, and regardless of what even smaller percentage by volume the color bodies may bear to the oil, intimate neutralizing contact by the caustic with substantially all of the color bodies is obtained, and since the caustic is of a higher concentration, this contact is obtained with a reduced amount of 65 saponification.

Some of the other desirable effects are: (1) Accomplishing a more thorough color removal than is possible by other processes even though no limitation of loss is placed upon the use of other processes. That is, even with higher loss experience other processes are not capable of producing as light an oil; (2) the process increases the effectiveness of the reagent to an extent that has a measurable economic benefit in saving of the reagent itself; (3) the process so completely uses the reagent within the short interval of time required for dispersion that little if any excess or unused caustic remains in contact with the fat. Unlike other processes where this condition prevails the loss experience is not effected by the time elapsing between initial contact and before separation of the two phases produced by the reagent. In conventional processes there remains an excess of unreacted caustic soda after mixing which saponifies fat when allowed to remain in contact with it thereby increasing the loss.

This circumstance is in practice minimized as far as possible by keeping the period of contact as short as practicable, which in most instances is a matter of minutes. With this process, however, experience has indicated that contact time after dispersion but before separation may extend into days without any very significant changes in either color or loss experience; (4) it has been found by experience that this process may be used to advantage either in conjunction with continuous or batch separation. When this dispersion is used as a continuous process it is followed by treatments involving the addition of water, the raising of the temperature and subjected to centrifugal force wherein the soap is separated from the fat.

With this usage it carries with it not only the principal advantage; i. e. achieving a useful color with a saving in loss, but combines this with a machinery simplification and an increase in capacity that is measured by throughput compared with conventional continuous mixers. When utilized as a batch process in conjunction with holding tanks within which separation of phases is carried out by addition of water, elevation of temperature while stirring and subsequent separation by gravity, the process has the advantage of achieving exceptionally high production rates with a minimum investment in machinery and a minimum expenditure of power.

In references to be made hereinbelow to oil colors, it is stated that all colors referred to in this application are measured by the official Lovibond standard, A. O. C. S. method No. Cc-13-B-45.

As a specific example of this process in commercial operation, an oil storage tank was partially filled with 125,000 pounds of cotton seed oil once refined through the Clayton caustic soda process. This oil entered the tank and was maintained at a temperature of 90° F. It had a color of 35 yellow and 13.1 red, and when tested by A. O. C. S. standard procedure, exhibited a bleach color of 35 yellow-5.0 red, both colors being on the Lovibond scale.

From the tank the oil was pumped by means of a centrifugal pump at a rate measured by a rota-meter of 21,000 lbs./hr. to a rotating blender operating at a speed of approximating 880 R. P. M. In such blender it was mixed with a measured stream of caustic soda. This caustic soda was a 50° Baumé solution pumped as a measured stream through a rota-meter at a rate of 25.2 lbs./hr. at a temperature of 90° F. Thus by measuring both oil and caustic rates, a 50° Baumé solution was applied to the extent of .12%.

The oil and caustic mixture flowed from the blender to the dispersor, in a closed system, thus requiring no additional pump, and entered the dispersor at a pressure of 19 lbs. per sq. inch. This dispersor was equipped with Carborundum disks seven inches in diameter, one stone being held stationary, the other revolving at 5400 R. P. M. The disks were held so as to maintain a spacing of .017 inch.

The oil and caustic were subjected to this stone abrasion as a continuous stream without any change in temperature, except that resulting from the heat of the reaction which raised the mixture temperature to approximately 94° F.

All of the oil in the original storage tank was passed as a mixture to a kettle equipped with an agitating device, steam coils, and appropriate openings. The time required for this operation approximated six hours. The oil and 150 lbs. of dispersed caustic accumulated at 94° F. at rest in the kettle. Heat was applied thereto by contact with the steam coils, while the product was slowly agitated in order to avoid local over-heating, until a temperature of 140° was obtained. At this point a measured quantity of water, amounting to 500 lbs., was sprayed over the surface of the oil from three spray nozzles at a rate of 25 lbs. per minute. The oil was continuously agitated while the water was being added, so as to expedite the contact of water with the reaction products of the caustic and oil. At this point the water-reaction product mixture was immiscible with the oil and showed a tendency to separate from the oil if not kept mechanically suspended by means of agitation.

The amount of water added was such as to bring about this reaction producing condition with reference to immiscibility and specific weight, but kept low enough to avoid a cloudy oil. The agitation was then discontinued and the oil allowed to separate from the reacting products which occurs by the oil rising to the top and the reaction products containing the coloring matter settles to the bottom. The kettle was allowed to stand at rest for three hours when the reaction products which are semi-liquid were drawn off. The oil remaining, and the reaction products, were weighed. The loss as oil shrinkage, as well as the refining loss, based on the weight of the reaction products, amounted to 0.6%. The color of the treated oil was reduced to 35 yellow-5.8 red from the original 35 yellow-13.1 red, and the bleachability improved from 35 yellow-5.5 red to 18 yellow-1.7 red when measured by standard A. O. C. S. methods, and Lovibond scale.

Illustrative of the loss saving accomplished by the process is the following comparison. Refined cotton seed oil having a color of 35 yellow-8.8 red and a bleach color of 35 yellow and 4.5 red was treated with caustic using the laboratory cup method, a method which Kroonen states produces comparable losses with "High-sheer" refining procedure. The same oil was treated on a conventional commercial plant scale using conventional methods in batch equipment. Additionally, the above described machine was used and the above described steps of this invention employed therewith in a parallel test. In each case the amount of lye was chosen to produce substantially the same color of refined oil and oil of substantially equal bleachability. The results are tabulated as follows:

	° B6. Caustic	Percent NaOH	Percent Loss	Bleach Color	Re- Refined Oil Color
60	Laboratory Cup Method... Special Mixer (This invention)	50	.25	2.0	15-1.5
	Conventional Plant Kettle Method	50	.10	0.90	15-1.5
		50	.27	3.95	15-1.3

65 The above tabulated results establish that the employment of the machine and process of this invention accomplished the same color as the laboratory cup method using less than half the amount of reagent and in doing so a loss was incurred which was again less than half of that experienced with the laboratory method.

70 While the amount of caustic chosen for use in the conventional kettle method was slightly excessive and thereby produced a somewhat better bleaching oil, the loss experienced was very high; so high that the savings by the process of this invention is readily apparent.

A second comparison between the proposed method and the kettle method carried out in batch equipment is illustrated by the following:

	°Bé Caustic	Percent NaOH	Percent Loss	Bleach Color	Re- Refined Oil Color
Conventional Kettle Method-----	50	.25	3.77	15-1.5	35y-4.6r
Special Mixer (This inven- tion)-----	50	.07	.58	15-1.5	35y-4.7r

This comparison illustrates that the conventional method of re-refining requires approximately four times the amount of reagent as is required by the process revealed herein and that the loss experienced by the conventional process is over six times that experienced by this new process.

The following table illustrates the difference between this special process and the continuous centrifugal re-

the preceding table in that production rates were tabulated ranging between 21,000 and 42,000 pounds per hour.

As a further illustration of the efficiency of this process and the associated low losses, the following tables are listed showing the oil treated by the conventional laboratory method as compared with the proposed method of this invention operating under different rates and different stone spacings. A comparison of the results clearly indicates that the proposed method can, as claimed above, accomplish more thorough color removal, and secondly, does this with less loss. At the same time the results illustrate the effectiveness of the type of dispersion used. As the throughput was decreased to one-fourth the starting rate and the spacing between the stones decreased to one-third the opening, there was significant improvement in the bleach color of the oil and no appreciable change in the loss experienced. This table illustrates within a partial operating range how much more effective the color removal may be and how much more the effectiveness of the reagent may be increased.

	Oil Rate Per Hour	Spacing Between Stones, Inches	°Bé Caustic	Percent NaOH	Re-Refg. Oil Color	Bleach Color	Percent Loss
Laboratory Cup Method-----	-----	-----	50	.25	6.6	20y-2.1r	2.2
Special Mixing (This invention):							
1-----	21,000	.017	50	.105	5.1	18y-1.7r	0.66
2-----	13,500	.013	50	.100	5.0	10y-1.5r	0.80
3-----	7,500	.009	50	.100	5.0	15y-1.4r	0.84
4-----	5,000	.006	50	.100	5.0	15y-1.4r	0.84

refining process, and further shows the advantages that might be expected from the utilization of this new process:

The following results illustrate not only the loss savings but also the completeness of the reaction when the dis-

	Type Oil Used	°Bé Caustic	Percent NaOH	Percent Loss	Bleach Color	Re- Refined Oil Color	Rate Per Hr.

"A" Oil has original color-35 yellow-8.2 red; original bleach color-35 yellow-3.4 red.

"B" Oil has original color-35 yellow-8.8 red; original bleach color-35 yellow-3.4 red.

"C" Oil has original color-35 yellow-9.5 red; original bleach color-35 yellow-5.0 red.

The significant points are as follows: (1) It is to be noted that the centrifugal process has limitations with reference to the ultimate bleachability. With oils as dark as the ones utilized in this test, which are often encountered, it was not possible to produce an oil bleaching better than 1.8 red even with a relatively large amount of caustic utilized. This puts a severe limitation upon the centrifugal or Clayton process, a limitation which is very significantly minimized by using the process of this invention. (2) Another pertinent point is illustrated by a comparison of the production rates achieved by the two processes. The centrifugal process when operating at rates between 6,000 and 12,000 pounds per hour utilized between 7 and 13 centrifuges and six mixers, while this special process operating with one mixer and the special dispersing machine along with one agitating tank was capable of rates up to 42,000 pounds per hour. The last two lines of the table immediately hereinabove further illustrate another operating range not shown in

perspective as illustrated by the effect of allowing the colloidal emulsion to remain unseparated for a period of eight days:

	°Bé Caustic	Percent NaOH	Percent Loss	Re- Refined Oil Color	Bleach Color
Laboratory Cup Method Special Mixer (This in- vention)-----	50	.25	2.0	5.3	15y-1.5r
Special Mixer (This in- vention) after allow- ing sample to stand 8 days before soap separation-----	50	.10	0.90	5.8	15y-1.6r
-----	50	.10	0.93	5.3	15y-1.5r

It is apparent that the reaction which takes place in the fraction of a second elapsing during the passage of the mixture between the stone was carried no further by allowing the mixture to stand for eight days.

The following comparison illustrates how the process

works equally well with batch gravity separation and continuous centrifugal separation:

	° Ba. Caustic	Percent NaOH	Percent Loss	Re-Refined Oil Color	Bleach Color
Laboratory Cup Method	50	.20	1.8	35y-5.7r	20-2.0
Special Mixer (This invention) and Kettle Separation 5 Hrs. after standing.	50	.055	0.64	35y-5.6r	17-1.8
Special Mixer (This invention) and Centrifugal Separation	50	.055	.56	35y-5.7r	20-2.1

Broadly this invention consists of a process of removing color from cotton seed oil, and the like, by re-refining methods, and such invention broadly takes in any method and structure which is capable of substantially instantaneously dispersing a caustic solution into the oil whereby the color bodies of the oil may be so amply and intimately contacted by a substantially reduced quantity of the caustic refining agent, as compared with conventional quantitative requirements, that a resultant substantially increased removal of color bodies at a substantially reduced refining loss may be obtained.

I claim:

1. A process for removing color from previously refined vegetable oils which comprises dispersing a caustic solution of at least 40° Baumé strength substantially instantaneously into the oil in not more than about one second and in an amount that the caustic soda is in the range of between 0.05 and 0.14 percent by weight of the mixture of oil and caustic solution and later separating the oil from the mixture.

2. A process for removing color bodies from previously refined vegetable oil which comprises dispersing into the oil in not more than about one second a caustic solution of from 40° Baumé to 60° Baumé strength and in an amount that the caustic soda constitutes between 0.05 to 0.14 percent by weight of the mixture and thereafter separating the oil from the mixture.

3. A process for removing color from previously refined vegetable oil which comprises blending said oil and a highly concentrated aqueous caustic solution of at least 40° Baumé strength and in an amount that the caustic soda content is less than 0.14 percent by weight of the blended mixture, forcing the blended mixture in a continuous stream of less than one-quarter inch thick through a space between relatively moving abrasive surfaces at a rate to instantaneously disperse the caustic soda into the oil in not more than about one second and thereafter separating the oil from the mixture.

4. A constant flow process of removing color bodies from previously refined vegetable oil, comprising adding to the refined oil a caustic solution of at least 40° Baumé strength and in an amount that caustic soda content is 5 by weight in the range of from about 0.055 to about 0.14 percent of the mixture, passing the mixture at the rate of 5,000 to 42,000 pounds per hour between opposing faces of relatively rotatable rotors operating at relative speeds of from 90 R. P. M. to 15,000 R. P. M. with said 10 opposing faces spaced apart from almost contact up to about one-quarter of an inch and thereafter separating the oil from the mixture, no portion of the mixture being between said rotor surfaces for more than about one second.
5. A constant flow process of removing color bodies from previously refined vegetable oil, comprising adding to the refined oil a caustic solution of at least 40° Baumé strength and in an amount that the content of caustic soda is by weight in the range of from about 0.055 to 20 about 0.14 percent of the mixture, passing the mixture in a continuously flowing thin stream of not more than one-quarter inch thickness between a pair of abrasive surfaces and moving the surfaces relative to one another at a rate of not less than 900 R. P. M. with the rate of 25 stream travel such that no portion of the mixture is between the abrasive surfaces for more than about one second and thereafter separating the oil from the mixture.
6. A process for removing color bodies from previously 30 refined vegetable oils which comprises adding to the oil about 0.14 percent or less by weight of caustic soda in an aqueous solution of from 40° Baumé to 60° Baumé strength and dispersing the caustic solution into the oil within a temperature range between approximately 60° F. and 150° F. and in a fraction of one second by passing 35 the mixture in a continuous stream at a rate of from 5,000 pounds to 42,000 pounds per hour between relative moving parts spaced apart not more than one-quarter of an inch and whose relative travel is at a rate of from about 1,649 feet per minute to about 27,489 feet per 40 minute and thereafter separating the oil from the mixture.

UNITED STATES PATENT OFFICE
CERTIFICATE OF CORRECTION

Patent No. 2,803,636

August 20, 1957

Porter A. Williams

It is hereby certified that error appears in the printed specification of the above numbered patent requiring correction and that the said Letters Patent should read as corrected below.

Column 7, line 57, for "yellow-5.0" read -- yellow-5.5 --; column 12, line 9, for "90 R. P. M." read -- 900 R. P. M. --.

Signed and sealed this 5th day of November 1957.
